DESIGN FOR A VESTEE SCARF

Lazare Louis, New York, N. Y.

Application February 9, 1943, Serial No. 109,510

Term of patent 7 years

To all whom it may concern:

Be it known that I, Lazare Louis, a citizen of the United States of America, residing in the city, county, and State of New York, have invented a new, original, and ornamental Design for a Vestee Scarf, of which the following is a specification, reference being had to the accompanying drawing, forming part thereof, wherein,

I claim:

The ornamental design for a vestee scarf, substantially as shown.

LAZARE LOUIS.
